United States Patent Office.

AMOS WILDER AND CYRUS W. STROUT, OF BOSTON, MASSACHUSETTS.

Design No. 2,940, dated February 25, 1868.

DESIGN FOR A CLOCK-FRONT.

The Schedule referred to in these Letters Patent and making part of the same.

TO ALL WHOM IT MAY CONCERN:

Be it known that we, AMOS WILDER and CYRUS W. STROUT, of the city of Boston, in the county of Suffolk, and State of Massachusetts, have originated and designed a new Pattern for Clock-Front, of which the following is a clear, full, and exact description, reference being had to the accompanying photograph, (or drawing,) making part of this specification.

This photograph represents a Masonic clock-front in bas-relief. On each side of the front is a recessed column, surmounted by an ornamental vase. These columns rest upon a base, which extends across the bottom of the front, the central part or ground extending above the columns in a pointed or Gothic form. On the right lower corner, in a recess of the base, is placed the emblem known in Masonry as the "Anchor." On the left lower corner, in a recess of the base, is the "Trowel." On the right, in a recess of the main base, is the "Ark;" in the centre, the "Square;" on the left, the "Plumb" and "Level." In the recess of the column on the right is placed the "Corinthian Column," surmounted by a globe, over which and on the right upper corner are placed the two "Parallel Lines," representing "St. John the Baptist" and "St. John the Evangelist," enclosing the "Circle" and "Book of Holy Scripture." In the recess of the column on the left is the "Corinthian Column," surmounted by a globe, above which is the "Ladder." In the lower centre of the ground, directly over and resting on the base, is the "Hour-Glass," surmounted by a "Bee-Hive." On its right are the "Three Steps;" on its left, the "Forty-Seventh Problem of Euclid." Directly over the "Bee-Hive," and occupying a central position on the ground, is a star; on its right, the "Sword," with point resting on the "Heart;" on the left, the "Sword" resting upon the "Constitution." Under the dial, and partially surrounding it, is the "Cable-Tow," under which, and above the "Star," are the "Gavel" and "Twenty-Four-Inch Gauge." Immediately above the dial, and in the top centre, is the "All-Seeing Eye," the whole being surmounted by the "Square and Compass," enclosing the letter "G."

Claim.

What we claim as our invention, and desire to secure by Letters Patent, is—
The design for a Masonic clock-front, as herein described and shown.
